[57] CLAIM

The ornamental design for a calculator telephone, as
shown and described.

DESCRIPTION

FIG. 1 is a front top perspective view of a calculator
telephone showing my new design;

FIG. 2 is a top plan view thereof;

FIG. 3 is a front elevation thereof;

FIG. 4 is a left side elevation thereof, the opposite side
is a mirror image of the side shown;

FIG. 5 is a rear elevation thereof; and

FIG. 6 is a bottom plan view thereof.

The broken lines representing the paper tape and tele-
phone cord are shown for illustrative purposes only.
